COOLING FIN

Roland Chilton, Ridgewood, N. J., assignor to The Reed Propeller Co., Inc., a corporation of New York

Application May 22, 1935, Serial No. 22,725

8 Claims. (Cl. 257—261)

This invention comprises an improved radiating fin means for use in heat interchangers in general, while a specific application to an air-cooled engine cylinder barrel is illustrated in the drawing.

One object of the invention is to provide means for attaching fins of high conductivity material, such as aluminum alloy, to a member of high strength material, such as steel. Such light alloy fins cannot be attached to steel members by brazing or welding, and a further object of the invention is to provide an attaching means giving good thermal contact between the fins and the member to which they are secured.

Another object is to reduce the cost of finned cylinder construction by eliminating the machining time involved in the current practice of turning the multiple fins from a thick forging which involves a large poundage of "scrap" material.

A further object is to provide a finned construction applicable to a cylinder having flanges or other enlargements at each end. A still further object is to provide a replaceable finning means and to provide a plurality of similar, easily fabricated fin units which may be assembled to produce a multi-finned organization for a cylinder.

Saving in weight and the ability to use closer fin spacing than is practicable with conventional methods are also included in the objects of the invention.

Other objects and advantages will be obvious from the following specification with reference to the drawing, in which:

Fig. 1 is a side view of an air-cooled cylinder barrel incorporating the fins of this invention;

Fig. 2 is a plan section through the barrel on the line 2—2 of Fig. 1 showing a pair of fin elements in separated relation;

Fig. 3 is a fragmentary section on the line 3—3 of Fig. 4;

Fig. 4 is a fragmentary section on the line 4—4 of Fig. 1; and

Fig. 5 is a section through a fin on the line 5—5 of Fig. 2.

In this drawing 10 designates a cylinder barrel having a conventional hold-down flange 12 and an enlarged threaded portion 14 at the upper end. It will be seen that between these projections the barrel has a smooth cylindrical exterior. The fins comprise semi-circular elements 16 assembled around the barrel as indicated in Figs. 1, 3 and 4. Each fin comprises an extended tapered portion 18 (Fig. 5) and a wider base

portion 20 which is machined on the inner surface 22 to be a shrink fit at assembly over the cylinder barrel. The width of the base portion 20 is such that each fin contacts its neighbors on the sides of the base. Each fin is provided with non-tapered end lugs 24 drilled with holes or eyes 26 to receive the long shear pins 28, the thickness of the lugs 24 being half that of the base portions 20. Thus, a set of fins may be assembled with the end lugs 24 in overlapping relation and the eyes 26 in alignment.

The fin elements may be cheaply and rapidly fabricated by a coining or cold forging operation from suitable stock whereby the dimensions may be held to close limits in quantity production. In order to control the bore of the fin assemblage to give the desired shrink fit over the barrel, a set of fins is preferably assembled on the shear pins 28 and supported on a suitable fixture for boring the inside diameter 22 to the desired fit. One hinge pin is then removed and the fins brought up to desired shrink temperature whereupon the set is wrapped around the barrel and the second hinge pin is then driven through the overlapping eyes.

By this method it is practicable to maintain a high intensity of pressure between each fin base and the contacted barrel wall. When this intimate contact is achieved the thermal drop across the joint becomes negligibly small. This desirable effect, coupled with the high conductivity material which may be used with the attachment methods of this invention, and further, the close finning spacing which may be economically used, gives a very much greater over-all cooling efficiency than can be obtained with integral steel fins which have lower conductivity, greater weight, and which are limited in height and spacing by manufacturing and conductivity limitations.

It should be mentioned that recent researches on the optimum fin proportions have demonstrated that high conductivity and much closer spacing and greater height than current practice, are desirable. As the output of air-cooled aircraft engines has been increased, limitations in the cooling capacity of the conventional fins have become of serious importance.

After the fins are assembled on the cylinder, the shrink fit of the fins will firmly hold the shear pins 28 in place. Assembly may be facilitated by providing bores 30 in the cylinder hold-down flanges 12 through which the shear pins 28 may be passed to engage the fin eyes 26. This likewise will serve as a positive circumfer-

ential locator for the fins with respect to the cylinder.

It is known that older types of construction contemplated forming screw threads on the outside of the cylinder barrel and screwing thereon a finned sleeve of different material. However, such a construction does not permit of closely spaced deep fins, and is much more expensive to manufacture.

10 While I have described my invention in detail in its present preferred embodiment, it will be obvious to those skilled in the art, after understanding my invention, that various changes and modifications may be made therein without departing from the spirit or scope thereof. I aim in the appended claims to cover all such modifications and changes.

What is claimed is:

1. The combination with a cylinder to be cooled, of semi-circular fins having end eyes assembled in overlapping relation, and secured around the cylinder by pins inserted through said eyes, the pin and eye axes being parallel to the cylinder axis, each said pin engaging more than two of said eyes.

2. The combination with a cylinder having exterior projections towards its ends, of fins comprising half rings assembled around the barrel with their ends in overlapping relation, and shear pins securing said fins by threading through holes in said overlapping ends, the pin and hole axes being parallel to the cylinder axis, and each said pin engaging the holes of more than two of said fins.

3. A stack of semi-circular fins having end eyes assembled in overlapping relation and secured by a pair of hinge pins to comprise a finned cylinder for encircling a cylindrical member.

4. An article of manufacture including a pre-formed semi-circular fin having an enlarged base contactable with a cylinder, and a relatively thin

fin portion terminating in thickened lugs each lug having an opening axially parallel to the fin axis.

5. An article of manufacture including pre-formed semi-circular fin having an enlarged base contactable with a cylinder, and a relatively thin fin portion terminating in thickened lugs of a thickness equal to half the thickness of the enlarged base.

6. A finning assemblage for a cylinder comprising a composite embracing cylinder composed of an assemblage of semi-circular fins overlapping at their ends, and hinge pins engaging holes formed near the ends of said elements for securing said assemblage in shrink fit relation about said cylinder.

7. A composite air-cooled cylinder assembly comprising in combination a cylinder of material having a relatively low coefficient of thermal expansion, a cooling fin assembly comprising semi-cylindrical halves having hinge pin eyes at their ends, and hinge pins engaging said eyes and axially parallel to the cylinder, said halves being formed of material of relatively high coefficient of thermal expansion, said halves being organized, upon elevation in temperature thereof, for wrapping about said cylinder and for attachment to one another by insertion of said hinge pins in the eyes of said cylinder halves and for attachment to said cylinder by shrinkage due to cooling of said fins from the elevated temperature.

8. A cooling fin assembly for embracement of a cylinder comprising finned half cylinders for fitting engagement around said cylinder, said half cylinders having, at the end elements thereof, coacting perforate lugs, and hinge pins engaging said perforate lugs for holding said half cylinders in assembled relation around said cylinder.
